[57] CLAIM

The ornamental design for an electronic equipment support shelf, as shown and described.

DESCRIPTION

FIG. 1 is a perspective view of an electronic equipment support shelf showing our design, a workstation being shown therein in broken lines for illustrative purposes only;

FIG. 2 is a front elevational view;

FIG. 3 is a right side elevational view, the undisclosed left side being a mirror image thereof;

FIG. 4 is a rear elevational view;

FIG. 5 is a top plan view; and

FIG. 6 is a bottom plan view thereof.
